United States Patent

Des. 242,369
Patented Nov. 16, 1976

242,369

JACK STRAW

Reet Thomas Jr., St. Louis, Mo., assignor to Steven Manufacturing Company, Hermann, Mo.

Filed Oct. 29, 1973, Ser. No. 410,624

Term of patent 14 years

Int. Cl. D21—01

U.S. Cl. D34—5 GP

FIG. 1.

FIG. 2.

FIG. 1 is an enlarged view, in perspective, of a jack straw, showing my new design; and

FIG. 2 is a side elevational view thereof, all side views being identical.

I claim:

The ornamental design for a jack straw, as shown and described.
